(57) **CLAIM**

The ornamental design for an octagonal bottle, as shown and described.

DESCRIPTION

FIG. 1 is a top perspective view of an octagonal bottle according to the present invention.

FIG. 2 is a bottom perspective view of the octagonal bottle of FIG. 1.

FIG. 3 is a front view of the octagonal bottle of FIG. 1, the rear view, left view, and right view being mirror images of FIG. 3 excluding the unclaimed thread element;

FIG. 4 is a top view of the octagonal bottle of FIG. 1; and, FIG. 5 is a bottom view of the octagonal bottle of FIG. 1. The broken lines shown in the drawings illustrate environmental subject matter only and form no part of the claimed design.

1 Claim, 4 Drawing Sheets
